(57) **CLAIM**

The ornamental design for a neckband for wearable air conditioner, as shown and described.

DESCRIPTION

FIG. 1 is a front perspective view of a neckband for wearable air conditioner showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view of an environment of use of the neckband for wearable air conditioner in FIG. 1. The broken lines depict portions of the neckband for wearable air conditioner that form no part of the claimed design. The broken lines in FIG. 8 show portions of the neckband for wearable air conditioner and the environmental structure that form no part of the claimed design.
